REFRIGERATING APPARATUS

Alex A. McCormack, Dayton, Ohio, assignor to
General Motors Corporation, Dayton, Ohio, a
corporation of Delaware

Application September 13, 1941, Serial No. 410,752

7 Claims. (Cl. 62-8)

This invention relates to refrigerating apparatus and more particularly to apparatus for controlling the operation of a refrigerating system.

It is an object of this invention to provide means whereby a given size motor-compressor unit may be used on widely varying refrigeration loads without sacrificing motor efficiency.

Another object of this invention is to provide means which makes it possible to operate a refrigerant compressor in a lower pressure range 10 so as to avoid excessive heating of the motor-compressor unit.

More specifically, it is an object of this invention to provide means for reducing the load on a compressor motor by restricting the flow of refrigerant to the compressor when the head pressure becomes excessive.

Another object is to provide a simple and inexpensive control device which may be added to existing refrigeration systems.

Further objects and advantages of the present invention will be apparent from the following description, reference being had to the accompanying drawing, wherein a preferred form of the present invention is clearly shown.

In the drawing:

Fig. 1 is a view partly diagrammatic and partly in section showing my invention applied to a conventional refrigerating system, and

Fig. 2 is an enlarged sectional view showing the refrigerant flow control device in that position which it occupies when the head pressure is excessively high.

Since the load on a refrigerating system frequently varies from day to day due to changes in the temperature of the condenser cooling medium and the like, it is necessary that the motor-compressor unit have a capacity considerably in excess of the average requirements. Since it is not practical from a standpoint of efficiency in operation to provide an oversized motor capable of operating the compressor at the highest pressures encountered, it is the purpose of my invention to provide a control means for preventing overloading of the motor at these high pressures. It is common practice to provide means for controlling the back pressure in a refrigerating system but all such means now in use either reduce the efficiency of the system or otherwise interfere with the proper operation of the system.

It is also common practice to provide protective devices such as high pressure cut outs for stopping the compressor or for otherwise rendering the compressor ineffective when the load on

the compressor becomes excessive. In many refrigeration installations, however, a high head pressure does not mean that operation of the compressor is no longer required since the high head pressure may be due to insufficient condenser capacity. Consequently, it is desirable to continue compressing refrigerant at times when both the back pressure and the head pressure exceed the pressures for which the compressor is designed to operate. In order to continue the operation of the compressor under such high pressure conditions, it is necessary to reduce the load on the compressor. The method and apparatus described herein makes it possible to continue the operation of the compressor at a reduced capacity when the pressure in the refrigerating system exceeds that for which the compressor is designed to normally operate.

Referring to Fig. 1, in which I have shown my 20 invention applied to a conventional refrigerating system, reference numeral 16 designates a conventional sealed motor-compressor unit. Reference numeral 12 designates the outer casing which encloses the motor-compressor mechanism 25 and which contains high pressure refrigerant vapor and a supply of lubricant 14. Reference numeral 18 designates a conventional rotary compressor having a suction line 18 and an outlet 20 provided with a valve 22. The compressed gas is 30 discharged directly into the outer casing 12 and is supplied to the condenser 24 through the vapor line 26 leading from the casing 12 to the condenser 24. The condensed refrigerant collects in the receiver 28 from which it is supplied to the evaporator 30. The flow of refrigerant from the receiver 28 to the evaporator 30 is controlled by a conventional thermostatic expansion valve 32. The thermostatic expansion valve 32 includes the usual thermostatic bulb 34 arranged 35 in thermal exchange relationship with the last pass of the evaporator in accordance with well known practice. The refrigerant vaporized in the evaporator 30 is returned to the compressor 40 through the suction line 36.

In order to control the flow of refrigerant from the evaporator to the compressor, I have provided a control unit designated in general by the reference numeral 38. The control unit 38 comprises a gas passage 38 and a valve element 48 carried by a plunger element 42. A spring 44 biases the valve element 48 into the fully open position in which it is shown in Fig. 1. In this position of the valve, the vapor leaving the evaporator 30 is free to flow without restriction through the passage 38 to the compressor inlet 50.

18. A screen filter element 46 is provided in the path of the refrigerant vapor flowing to the compressor 16. A check valve 48 is also provided in the vapor line so as to prevent the flow of refrigerant or lubricant from the compressor into 5 passage 39 and the vapor line 36.

The control unit 38 includes a passage 50 which communicates with the motor-compressor casing 12 at a point below the level of the lubricant 14. The lubricant 14 is subjected to a pressure corresponding to the high side pressure and is used for controlling the operation of the valve 40. The passage 50 supplies lubricant to the lower end of the valve plunger 42, with the result that as the pressure on the lubricant becomes excessively high the plunger 42 together with its associated valve element 40 is moved upwardly so as to restrict the return of refrigerant vapor to the compressor. Inasmuch as it is not the purpose of the valve 40 to completely cut off the flow of refrigerant to the compressor, a small amount of clearance 52 is provided between the valve element 40 and the outer walls of the refrigerant passage 39.

The lubricant which contacts the lower end of the plunger 42 not only serves to lubricate the plunger but also serves as a liquid seal preventing the leakage of high pressure gas past the plunger into the low side of the system.

By adding a simple control of the type disclosed herein to an ordinary refrigerating system, the same motor and condenser is capable of operating at higher condensing temperatures. Thus, by using my improved control, a conventional five horse power unit may be used in a system which would otherwise require a six or seven horse power unit since the compressor will continue to operate at the higher refrigerant pressures which occur only during peak loads. As pointed out hereinabove, the valve 40 will restrict the flow of refrigerant to the compressor at the higher head pressures but the compressor will still operate to compress refrigerant vapor at a high rate. Since it is not necessary to provide an oversized motor to provide refrigeration during peak loads, it is apparent that a five horse power refrigerating system constructed in accordance with my invention operates more efficiently at lower loads than a system using a larger motor.

Since the peak load for which a refrigerating system must be designed may never be reached, it is apparent that a system designed according to my invention will operate with the valve 40 fully open in many installations for a major portion of the time.

While the form of embodiment of the invention as herein disclosed, constitutes a preferred form, it is to be understood that other forms might be adopted, all coming within the scope of the claims which follow.

What is claimed is as follows:

1. In combination; an evaporator, a condenser; a compressor including a lubricant supply casing into which said compressor discharges; refrigerant flow connections between said evaporator, condenser and compressor including a suction line between said evaporator and the inlet of said compressor; and means for restricting the flow of refrigerant in said suction line; said means comprising a passage leading from a point below the lubricant level in said lubricant supply casing to the suction line, a plunger disposed in said passage preventing the flow of lubricant through said passage and having means for restricting the flow of refrigerant in said suction 75

line in a predetermined position of said plunger, and spring means for opposing the force exerted by the lubricant against said plunger.

2. In a refrigerating system, a compressor, an evaporator, a condenser, refrigerant flow connections between said compressor, condenser and evaporator, refrigerant flow control means between said evaporator and condenser separating said system into a high pressure portion and a low pressure portion, means providing a passage from the high pressure portion to the low pressure portion, a piston in said passage having one end subjected to the high pressure and the other end subjected to the low pressure, means operated by said plunger restricting the flow of refrigerant to said compressor, and means for supplying lubricant to the high pressure end of said passage so as to lubricate said piston and provide a liquid seal between said piston and the walls of said passage.

3. In combination; a compressor; a lubricant supply casing enclosing said compressor; means whereby said compressor discharges into said casing; a suction line leading to the inlet of said compressor; and an adapter provided in said suction line including means for restricting the flow in said suction line; said adapter having a passage communicating with the interior of said lubricant supply casing at a point below the lubricant level therein and also communicating with the suction line, a plunger disposed in said passage preventing the flow of lubricant through said passage and having means for restricting the flow of refrigerant in said suction line in a predetermined position of said plunger, and spring means for opposing the force exerted by the lubricant against said plunger.

4. In a compressor including a lubricant supply casing into which said compressor discharges; a suction line leading to the inlet of said compressor; and means for restricting the flow in said suction line; said means comprising a passage leading from a point below the lubricant level in said lubricant supply casing to the suction line, a plunger disposed in said passage preventing the flow of lubricant through said passage and having means for restricting the flow of refrigerant in said suction line in a predetermined position of said plunger, and spring means for opposing the force exerted by the lubricant against said plunger.

5. In a compressor having a low pressure inlet chamber and a high pressure outlet chamber, means providing a passage from the high pressure chamber to the low pressure chamber, a piston in said passage having one end subjected to the high pressure and the other end subjected to the low pressure, means operated by said plunger restricting the flow to the inlet of said compressor, and means for supplying lubricant to said passage so as to lubricate said piston and provide a liquid seal between said piston and the walls of said passage.

6. In combination; an evaporator; a condenser; a compressor including a lubricant supply casing into which said compressor discharges; refrigerant flow connections between said evaporator, condenser and compressor including a suction line between said evaporator and the inlet of said compressor; and an adapter mounted in said suction line including means for restricting the flow of refrigerant in said suction line; said adapter comprising a passage leading from a point below the lubricant level in said lubricant supply casing to the suction line; a plunger dis-

posed in said passage preventing the flow of lubricant through said passage and having means for restricting the flow of refrigerant in said suction line in a predetermined position of said plunger.

7. In combination; an evaporator; a condenser; a compressor including a lubricant supply casing into which said compressor discharges; refrigerant flow connections between said evaporator, condenser and compressor including a suction line between said evaporator and the inlet of said compressor; and means for restricting the flow of refrigerant in said suction

line; said means comprising a passage leading from a point below the lubricant level in said lubricant supply casing to the suction line, a plunger disposed in said passage preventing the flow of lubricant through said passage and having means for restricting the flow of refrigerant in said suction line in a predetermined position of said plunger, and spring means for opposing the force exerted by the lubricant against said plunger, said passage and said plunger being provided in an adapter mounted externally of said casing.

ALEX A. McCORMACK.
